A. T. GARDEN

OIL BURNER

Filed Jan. 15, 1923

Inventor,

A.T. Garden.

By *Chasnow & Co.*
Attorneys.

UNITED STATES PATENT OFFICE.

ALEXANDER T. GARDEN, OF AUGUSTA, KANSAS.

OIL BURNER.

Application filed January 15, 1923. Serial No. 612,738.

To all whom it may concern:

Be it known that I, ALEXANDER T. GARDEN, a citizen of the United States, residing at Augusta, in the county of Butler and 5 State of Kansas, have invented a new and useful Oil Burner, of which the following is a specification.

This invention relates to burners for vaporizing and burning hydro-carbons in 10 which the oil is atomized and driven into a combustion chamber by a jet of steam.

The object of the invention is to provide a burner of this character so constructed as 15 to be used in connection with the oil regulator shown and described in patent application Number 496,711 filed August 29, 1921 and allowed November 29, 1922, whereby the oil and steam are regulated before reaching the burner and pass unobstructed there- 20 through, the burner being in no sense a regulator, and is valveless.

Another object is to provide a burner of 25 this character in which the oil gravitates to the burner and is not injected by any means.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed may be made within the scope of what is claimed without departing from the spirit of the invention.

The accompanying drawing represents a 40 longitudinal section of a burner constructed in accordance with this invention.

The burner constituting this invention is 45 designed especially for use with the oil regulator above referred to and comprises a casting 1 having a bore extending longitudinally therethrough and internally threaded at its outer end as shown at 2 for connection with a steam pipe. The threaded portion of this bore merges at its inner end into a reduced extension 3 terminating at the front of the casting in a discharge nozzle 4.

This casting 1 is threaded into a T-shaped 50 shell 5, the stem 6 of which is internally threaded for connection with an oil supply pipe and constitutes the oil inlet of the burner.

The oil entering through this inlet 7 gravitates to the interior of the shell which 55 is provided with an oil excess chamber 8 surrounding the nozzle 4.

The combined steam and oil discharge 9 leads from the casting 5 in alignment with the nozzle 4 and at right angles to the oil 60 inlet 7 and is externally threaded as shown at 10 for the engagement of the cap to be used when cleaning out the oil line.

As shown, the casting 1 has a hexagonal outer face 11 for the application of a wrench 65 when assembling the parts.

This burner which as above set forth is primarily intended for use in connection with the oil regulator above referred to, has steam admitted thereto through the inlet 70 2 and the oil through the inlet 7, the steam passing out through the nozzle 4 operating to suck with it oil from the pocket 8 which is vaporized and sprayed through the discharge 9 into the combustion chamber (not 75 shown).

From the above description it will be obvious that this burner is constructed of two 80 parts only, which are united by a threaded connection shown at 12.

Briefly considered, the device forming the subject matter of this application comprises a T-shaped shell 5 including a stem 6 and oppositely disposed arms 9 and 19, the arm 19 having a conical bore 12 and the 85 arm 9 having a cylindrical bore 9^a, there being a chamber 8 in the shell 5 and connecting the bores 12 and 9^a, the chamber tapering from its intermediate portion to its ends, the shell having a passage 20 communicating with the stem 6 and with the chamber 8 and of the same diameter as the length of the chamber, the conical nozzle 4 being mounted in the tapered bore 12 and extending through the chamber 8 to the 90 place 21 of juncture between the chamber and the cylindrical bore 9^a.

I claim:—

A device of the class described comprising 100 a T-shaped shell including a stem and oppositely disposed arms, one arm having a conical bore and the other arm having a cylindrical bore, there being a chamber in the shell and connecting the bores, the chamber tapering from its intermediate portion to its ends, 105 the shell having a passage communicating

with the stem and with the chamber and of the same diameter as the length of the chamber, and a conical nozzle mounted in the tapered bore and extended through the chamber to the place of juncture between the chamber and the cylindrical bore.

In testimony that I claim the foregoing

as my own, I have hereto affixed my signature in the presence of two witnesses.

ALEXANDER T. GARDEN.
